UNITED STATES PATENT OFFICE.

JOSEPH J. ARONOFF, OF TRENTON, NEW JERSEY.

COLLAPSIBLE RECEPTACLE.

1,111,428.

Specification of Letters Patent. Patented Sept. 22, 1914.

Application filed December 9, 1913. Serial No. 805,581.

To all whom it may concern:

Be it known that I, JOSEPH J. ARONOFF, a citizen of the United States, residing at Trenton, in the county of Mercer and State 5 of New Jersey, have invented new and useful Improvements in Collapsible Receptacles, of which the following is a specification.

This invention relates to an improved collapsible receptacle for merchandise, parcel post mail matter, and the like.

One of the objects of the invention is to provide a receptacle of this character of maximum capacity which may be readily 15 collapsed and folded into compact form of minimum size for convenience in transportation and the like.

A further object is to provide a receptacle of the character referred to which may 20 be readily opened out to receive the material to be placed into it, and so constructed that the parts cannot accidentally collapse.

A further object is to provide means whereby the receptacle may be conveniently 25 moved from place to place, when filled, or during the process of filling.

The invention will be hereinafter fully set forth and particularly pointed out in the claims.

30 In the accompanying drawing:—Figure 1 is a perspective view illustrating my improved receptacle. Fig. 2 is a longitudinal sectional view thereof. Fig. 3 is a detail view illustrating one corner of the receptacle, parts being shown in section. Figs. 4 and 5 are views illustrating details of Fig. 3. Fig. 6 is a perspective view showing the receptacle partially collapsed. Fig. 7 is a view illustrating the collapsed receptacle.

40 Referring to the drawing, 10 designates a base of any suitable or preferred construction, mounted upon casters 11. To the corners of base 10 are secured angle braces each formed with a wing 12 engaging the end

45 portion of the base 10, and a wing 13 engaging the side portion of said base. Side frames for the receptacle are formed of U-shaped rods 14 the depending ends 15 of which are hinged or pivoted to the wings 12 of the respective angle braces. Corresponding end frames 16 are also formed of U-shaped rods the depending ends 17 of which are pivoted to the wings 13 of the corner

braces. It will be noted that each side frame adjacent the depending ends 15, is provided with notches 18 to receive the depending ends of the contiguous end frames so as to brace or lock the latter in their open or upright positions. The sides and ends of the receptacle are formed of any suitable flexible material possessing the requisite strength, such as canvas, duck, or the like. Said flexible material is preferably permanently united to the side frames by passing the upper edge portions of the sides, around the main portions of the respective side frames and sewing or otherwise securing said edges in place. Likewise the upper edge of the flexible material at the ends of the receptacle is provided with complementary fastenings, such as stud and socket devices 19, whereby said edges may be removably connected with the main portions of the end frames 16. A cover 20 is provided, the same being formed of flexible material stiffened at its edges by means of a frame 21, the edge of the material being passed around said frame and suitably secured. Said cover is connected with one of the sides of the receptacle by means of a hinge 22, preferably formed of the same material as the body and top of the receptacle. Suitable leather hasps 23 are secured to the free edge of the cover 20, and ring like staples 24 are pivotally connected to the upper edge of one of the sides of the receptacle. It will be noted that the hasps may lie flat against the side of the receptacle when the latter is folded, or if for any reason the hasps are not used. The stud and socket devices 19 perform an important function in that they serve to unite the end walls of the receptacle to the end frames in such manner as to prevent surreptitious removal of the contents of the receptacle.

In order that the receptacle may be moved around readily upon the casters 11 I provide a handle 25 which is connected with suitable hooks or the like secured to the forward end of the base 10. The handle is hinged so as to permit the same to lie flat against the top of the receptacle when the same is collapsed. When the receptacle is in collapsed position the parts are held from separating by straps 26 each secured at one end to the respective side edges of the cover 20, the other end of

each strap being provided with a socket to engage a complementary stud 27 secured to the base 10.

In practice, the receptacle is rendered ready for use by first lifting the top or cover 20, and then moving the side frames outwardly upon their hinge connections until vertical. The end frames are then swung outwardly upon their hinge connection until they engage the notches 18, outward movement of the sides being prevented because of the connection of the flexible sides and ends at the corners of the receptacle. The cover may then be closed over the top of the receptacle thus provided. The receptacle is now in condition to be moved from place to place to receive the merchandise, packages, parcel post matter, or the like, as the case may be, and after the receptacle has been filled the cover may be locked by passing the staples 24 through the hasps 23 and then locking the same in any suitable manner, as for instance, by padlocks (not shown). The receptacle may then be placed in a delivery wagon, or other conveyance, as may be desired, for the purpose of transporting the receptacle and its contents to a distant point. After the receptacle has been emptied it may be readily collapsed by first detaching the flexible covering from the end frames 16, then pushing in the end frames and then successively pushing in the side frames, the flexible end portions folding in neatly so that the cover carrying the straps 26 comes on top. The handle 25 is then folded back and over the collapsed receptacle the straps 26, after being passed over the rods forming part of said handle, are engaged with their respective securing device. The receptacle has thus been collapsed into an exceedingly compact form so as to take up but little room for return transportation.

From what has been said it will be observed that I have produced a collapsible receptacle that is exceedingly simple in construction and which may be manufactured at low cost. It will be further noted that the same is particularly valuable for use in post offices for the handling of parcel post matter, although I do not desire to limit myself in this particular, as it also has a wide field of usefulness in connection with the handling of merchandise and miscellaneous packages of all kinds.

Having thus explained the nature of my invention, and described an operative manner of constructing and using the same, although without attempting to set forth all of the forms in which it may be made, or all of the modes of its use, what I claim is:—

1. A collapsible receptacle of the character described comprising a base, side frames hinged to the ends of said base, end frames hinged to the sides of said base near

the ends thereof between said side frames to brace the latter when in open position, and flexible sides and ends secured to said side frames and to said base, said flexible sides and ends being connected at the corners of the receptacle to limit outward movement of the upper edges of said side frames.

2. A collapsible receptacle of the character described comprising a base, side frames formed of U-shaped rods having their ends hinged to the ends of said base near the ends thereof, end frames also formed of U-shaped rods hinged to the sides of said base between said side frames to brace the latter when in open position, and flexible sides and ends secured to said side frames and to said base, said flexible sides and ends being connected at the corners of the receptacle to limit outward movement of the upper edges of said side frames.

3. A collapsible receptacle of the character described comprising a base, side frames hinged to the ends thereof and provided with notches in their inner faces, end frames hinged to the sides of said base near the ends thereof between the side frames and engaging said notches when in open position, and flexible sides and ends secured to said side frames and to said base, said flexible sides and ends being connected at the corners of the receptacle to limit outward movement of the upper edges of said side frames.

4. A collapsible receptacle of the character described comprising a base, side frames formed of U-shaped rods hinged to the ends of said base and provided with notches in their inner faces, end frames formed of U-shaped rods hinged to the sides of said base near the ends thereof between said side frames and engaging said notches when in open position, and flexible sides and ends secured to said side frames and to said base, said flexible sides and ends being connected at the corners of the receptacle to limit outward movement of the upper edges of said side frames.

5. A collapsible receptacle of the character described comprising a base, side frames hinged to the ends of said base, end frames hinged to the sides of the base near the ends thereof between the side frames to brace the latter when in open position, and flexible sides and ends secured to said side frames and to said base, said flexible ends limiting outward movement of the upper edges of said side frames, said flexible sides and ends being connected at the corners of the receptacle.

6. A collapsible receptacle of the character described comprising a base, side frames hinged to the ends thereof, end frames hinged to the sides of said base near the ends thereof to brace the side frames when in open position, flexible sides and ends se-

cured to said side frames and to said base, said flexible sides and ends being connected at the corners of the receptacle, casters secured to said base, and a handle also connected with said base.

7. A collapsible receptacle of the character described comprising a base, side frames hinged to the ends thereof, end frames hinged to the sides of said base near the ends thereof to brace the side frames when in open position, flexible sides and ends secured to said side frames and said base, said flexible sides and ends being connected at the corners of the receptacle, and means for holding the parts in collapsed relation.

8. A collapsible receptacle of the character described comprising a base, side frames hinged to the ends thereof, end frames hinged to the sides of said base near the ends of the latter to brace the side frames when in open position, flexible sides and ends secured to said side frames and to said base, said flexible sides and ends being connected at the corners of the receptacle, a handle also connected with said base, and means for holding said handle and said receptacle in collapsed relation.

9. A collapsible receptacle of the character described comprising a base, side frames hinged to the ends thereof, end frames hinged to the sides of said base near the ends of the latter to brace the side frames when in open position, flexible sides and ends secured to said side frames and said base, said flexible sides and ends being connected at the corners of the receptacle, a cover hinged at one edge to one of the sides of the receptacle, and locking means for the opposite edge of said cover.

40 10. A collapsible receptacle of the character described comprising a base, side frames hinged to the ends thereof, end frames hinged to the sides of said base near the ends of the latter to brace the side frames when in open position, flexible sides and

ends secured to said side frames and said base, said flexible sides and ends being connected at the corners of the receptacle, a cover hinged at one edge to one of the side frames of the receptacle, locking means for the opposite edge of said cover, straps secured to said cover, and means coöperating with said straps for holding the parts in collapsed relation.

11. A collapsible receptacle of the character described comprising a base, side frames hinged to the ends thereof, end frames hinged to the sides of said base near the ends of the latter to brace the side frames when in open position, flexible sides and ends secured to said side frames and said base, said flexible sides and ends being connected at the corners of the receptacle, and a cover hinged at one edge to one of the sides of the receptacle, said cover being formed of flexible material having its edges provided with a stiffening frame.

12. A collapsible receptacle of the character described comprising a base, side frames hinged to the ends thereof, end frames hinged to the sides of said base near the ends of the latter to brace the side frames when in open position, flexible sides and ends secured to said side frames and said base, said sides and ends being connected at the corners of the receptacle, a cover hinged at one edge to one of the sides of the receptacle, said cover being formed of flexible material having its edges provided with a stiffening frame, means for locking said cover in closed position, and means carried by said cover for holding the parts in collapsed relation.

In testimony whereof I have hereunto set my hand in presence of two subscribing witnesses.
